UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

THREAD-CONTROLLER FOR OVERSEAMING-MACHINES.

1,197,055.

Specification of Letters Patent.

Patented Sept. 5, 1916.

Application filed October 28, 1913. Serial No. 797,775.

To all whom it may concern:

Be it known that I, LANSING ONDERDONK, a citizen of the United States, residing at New York city, in the county of New York, State of New York, have invented certain new and useful Improvements in Thread-Controllers for Overseaming-Machines, of which the following is a description, reference being had to the accompanying drawing, and to the figures of reference marked thereon.

The invention relates to new and useful improvements in overseaming machines and more particularly to what is known in the art as a "cup feed machine".

An object of the invention is to provide a machine of the above type with thread controlling devices which operate to take up the looper thread twice during each cycle of operation of the stitch forming elements, said controlling devices being timed to draw the looper thread taut prior to the needle point passing between the body of the looper and the looper thread, so that the needle will, with certainty, enter the looper thread loop, and also to draw the looper thread taut just as the needle loop is being shed from the looper and the stitch set, and just as the looper point is advancing into the needle loop so as to prevent the looper thread from buckling and thus crowding the needle loop to one side and causing the skipping of the stitches.

A further object of the invention is to provide a thread controlling device of the above character with a coöperating thread controlling device for the needle thread, which pulls on the needle thread just as the needle loop is dropped from the looper so as to draw the stitch taut and set the same. The needle thread controller also pulls slightly on the needle thread, just as the point of the needle is leaving the material to give a still further stitch setting pull on the needle loop.

A still further object of the invention is to provide thread controlling devices for both the looper and needle threads, wherein the acting or movable elements are all mounted upon the looper supporting rod and moved in timing therewith.

These and other objects will in part be

obvious and will in part be hereinafter more fully disclosed.

In the drawings, which show by way of illustration one embodiment of the invention, Figure 1 is a vertical sectional view through a machine embodying my improvements, and showing the devices for operating the looper and the needle in side elevation; Fig. 2 is a top plan view of the machine with the cover plate removed; Fig. 3 is a plan view of the feed wheels, stitch finger, the stitching elements, and the immediate thread guides therefor, showing the looper in position for the needle to enter the needle loop; Fig. 4 is a view similar to Fig. 3, showing the looper moved to a point for entering the needle loop; Fig. 5 is a perspective view of the needle and looper, the thread controlling devices, the feed wheels, and the needle guide and stitch finger, showing the looper as directly over the fabric on its way to the inside of the fabric; Fig. 6 is a perspective view similar to Fig. 5, showing the looper just as it is entering the needle loop; Fig. 7 is a similar view showing the looper positioned for the entrance of the needle into the looper thread loop; Fig. 8 is a similar view, showing the looper moved to the position for shedding the needle loop. Fig. 9 is an enlarged detail showing the relation of the looper to the needle when the needle is passing between the looper thread and the body of the looper.

The invention consists generally in an overseaming machine wherein two feed wheels are so disposed as to support the fabric or material being stitched in substantially a vertical plane, and these feed wheels are intermittently operated to feed the fabric or material to the stitching mechanism. The material being stitched extends slightly above the upper edges of the feed wheels, and a needle carried by a horizontally reciprocating needle bar moves into and out of the material, while a looper, preferably of the thread-carrying type, coöperates with the needle first on one side of the material and then the other, moving over the edge of the material so as to lay the threads around the edge of the material, thus forming an over edge connecting seam for the pieces of fabric or material being stitched.

Cooperating with the looper are thread controlling devices which operate upon the looper thread to draw the same taut when the needle loop is being shed from the looper 5 and the stitch is being set, and also when the looper point is entering the needle loop. These controlling devices also draw the looper thread taut just as the point of the needle is passing between the body of the 10 looper and the looper thread so as to insure the needle entering the looper thread loop.

Cooperating with the needle are thread controlling devices which operate to draw on the needle thread as a needle loop is shed 15 from the looper so as to draw up the loops and set the stitch, and which thread controlling devices also draw on the needle thread as the point of the needle is leaving the material to cause a final setting of the stitch.

20 Referring more in detail to the drawings, my improved machine consists of a supporting casing 1, which houses the operating devices for the stitch forming elements. Mounted in suitable journals carried by the 25 casing is a main shaft 2. This main shaft carries a belt wheel 3 at each end thereof. At the forward part of the casing there is a suitable bracket in which is mounted a vertical shaft carrying a feed wheel 4. Pivoted 30 at 5 to this bracket is a second movable bracket 6 in which is journaled a shaft carrying a feed wheel 7. The fabric or material to be stitched is clamped between the feed wheels 4 and 7 so that the edges extend 35 slightly above said feed wheels. The shafts carrying the feed wheels have intermeshing gears 8 and 9 respectively, so that these feed wheels are caused to travel in unison in opposite directions, and, therefore, said feed 40 wheels coöperate in feeding the fabric or material being stitched to the stitching mechanism. The shaft carrying the feed wheel 4 is intermittently actuated by suitable mechanism.

45 The needle 10 of the stitch forming mechanism is mounted in a needle bar 11 and reciprocates in bearings 12 and 13. These bearings are so disposed that the needle bar reciprocates substantially in a horizontal 50 plane, and the needle is moved back and forth directly above the upper edges of the feed wheels, and will be caused to penetrate the edges of the material extending above the feed wheels. A collar 14 is fixedly secured to the needle bar between the bearings 12 and 13. This collar has a depending lug which is connected by a link 15 to a lever 16. This lever 16 is fulcrumed so as to turn freely on a supporting shaft 17, which, in 55 turn, is mounted in suitable journals 18 carried by the casing. The lever 16 between its ends carries a ball stud 19, to which is pivotally connected a link 20. This link 20 at its opposite end is formed integral with 60 an eccentric strap 21, which coöperates with

an eccentric 22 on the main shaft 2. As the main shaft 2 rotates, this eccentric 22 positively vibrates the lever 16 back and forth, and the lever, through the link connection 15, positively reciprocates the needle. 70

Coöperating with the needle 10 is a looper 23. This looper 23 is mounted in a looper rod 24, which, in turn, is mounted in a looper rod support 25. This looper rod support is in the form of a double yoke, which 75 carries at each side a short stud shaft and these shafts are mounted in suitable journals 26 carried by the casing 1. These stud shafts are in axial alinement and this permits the double yoke looper rod support to 80 swing so as to move the rod in a vertical plane. The looper rod is reciprocated back and forth in the looper rod support 25 by a lever 27, which is fulcrumed on the shaft 17 and turns freely thereon. This lever at 85 its upper end is connected to a ball stud mounted on a sleeve 28, journaled between fixed collars 29 on the looper rod. These fixed collars 29 prevent the sleeve 28 from moving endwise, but also allow the looper 90 rod to turn in the sleeve. The lever 27 has a laterally extending ball stud between its ends to which is pivotally connected a link 30. This link 30 is formed integral with an eccentric strap which cooperates with an eccentric on the main shaft. The rotation of the main shaft will, through the lever 27, move the looper rod endwise in the looper rod support 25, and this endwise movement of the looper rod carries the looper from one 100 side of the material to the other, and thus lays the threads over the edge of the material. 95

The looper rod is oscillated in its support to carry the looper into and out of the 105 needle loop by a link 32, which is connected at its upper end to a laterally projecting stud 33 fixedly attached to the looper rod. This link 32 is formed integral with an eccentric strap which coöperates with an eccentric 34 on the main shaft 2. As the main shaft rotates the link will be moved endwise and in turn cause the looper rod to oscillate. 110

The looper is raised as it moves from one side of the material to the other so as to be 115 carried over the edge of the material by imparting a swinging movement to the looper rod support 25. Mounted on a cross shaft 35 journaled in suitable bearings in the casing is a lever 36. This lever at its lower end is pivoted at 37 to a link 38 which is formed integral with an eccentric strap coöperating with an eccentric 39 on the main shaft. The lever 36 at its upper end is pivoted to a link 40, and this link is, in turn, pivoted to a ball 120 stud 41, carried by a collar 41^a, clamped on the looper rod support 25. The pivotal connection between the link 40 and the lever 36 moves from one side of a line passing through the fulcrum of the lever and the ball 130

stud 41 to the other side thereof, so that, as the lever 36 is given one complete oscillation, the looper rod will be lowered and raised twice.

- 5 It will be apparent from the above description that I have provided three separate eccentrics, each of which is connected positively and by a direct series of connections either to the looper rod or the looper 10 rod support. These eccentrics are so timed as to coöperate with each other in moving the looper, but the movement imparted to the looper from each eccentric is, in a measure, distinct and independent from that im- 15 parted by the other eccentrics. These eccentrics are so timed that the looper moves forward into the needle loop thrown out by the needle after the needle has penetrated the material, after which the looper, still re- 20 maining in the needle loop, is raised and then moved laterally to the other side of the material where it is lowered and positioned so that the needle on its next stroke can pass between the looper thread and the body of 25 the looper, after which the looper is raised and again swung so as to be withdrawn from the needle loop to permit the drawing up of the loops. The looper is then carried across 30 the plane of the material to the other side thereof, and is ready to again enter the needle loop.

Coöoperating with the needle is the usual needle guide for guiding the needle, which needle guide is fixed to the outer movable 35 bracket and overhangs the outer feed wheel. Also coöoperating with the needle is a stitch finger, over which the thread loops are laid. These parts, however, may be of the usual type and form no part of the present invention.

This looper operating mechanism and also the needle operating mechanism, whereby the stitch forming elements are given positive movements in proper timed relation to 45 each other, form no part of the present invention, but are shown, described and claimed *per se* in my co-pending application filed of even date herewith, Serial No. 797,773.

- 50 The needle thread is led from the supply through suitable tension disks 42, which are normally pressed together by a spring 43. Said needle thread *n* then passes through a thread guide 44 which is adjustably fixed 55 to the main casing of the machine by a screw 44^a and projects laterally therefrom. By loosening the screw 44^a, the shank of the thread guide may be moved into or out of the socket supporting the same for adjusting the position thereof. Mounted on the 60 looper supporting head of the looper supporting rod is a thread guide 45 which has an elongated thread eye 46. This thread eye 46 extends in a direction substantially parallel with the looper supporting rod, and the
- needle thread passes through said elongated eye. The needle head is formed with a thread eye 47 and a second thread eye 48. The needle thread *n* passes from the elongated thread eye 46 in turn through the 70 thread eyes 47 and 48 and thence to the eye of the needle. This thread eye 46 moves with the looper rod and will, therefore, have an up and down movement, a back and forth movement, and an oscillating movement. 75 Said thread eye is so positioned relative to the fixed thread guide 44 that said thread eye 46 moves away from the fixed thread guide 44 when the looper moves over the edge of the material, and continues this 80 movement away from the thread guide 44 until the looper reaches the lower end of its stroke. Just before the needle reaches the outer end of its stroke, the looper reaches the position in which the previous needle 85 loop is shed, and this continued drawing on the needle thread causes the loops to be drawn up preparatory to forming of the next stitch. As the looper moves forward to enter the needle loop, the thread eye 46 90 will be raised, swinging about the looper rod axis, and this will release the draw on the needle thread sufficient to allow the needle which is being refracted at this time to throw out the needle loop for the entrance 95 of the looper. As the looper moves to the other side of the material and drops to position its thread for the needle to pass between the looper thread and the body of the looper, the new formed needle loop carried 100 by the looper is laid across the stitch finger and the needle thread will be drawn on slightly at this time in order to coöperate with the looper in the final drawing of the loops to secure the final setting of the stitch. 105 Inasmuch as this thread eye for the needle thread is carried by the looper, notwithstanding the fact that the looper follows a very irregular path, due to the combined movements of the looper, still this thread 110 guide will move in proper timing therewith and draw on the thread at the times desired.
- The looper thread *l* passes through tension disks 49 and thence through a fixed thread guide 50, which is adjustably secured to the 115 main casing by a screw 50^a and projects laterally therefrom. By loosening the screw 50^a, the shank of the thread guide 50 may be moved into and out of its socket for adjusting the position of the thread guide. 120 Said looper thread *l* is led from the fixed guide 50 to a thread guide 51 fixed to the looper head, and thence passes to the eyes of the looper. This thread guide 50 is so positioned relative to the thread eye 51 that 125 when the looper is moving to the inner side of the fabric and depressed in order to position the looper thread so that the needle will pass between the same and the body of the looper, said thread eye 51 is moving away 130

from the fixed thread guide 50, and draws on the looper thread. This takes up the looper thread as the looper moves toward the thread guide 50 and also draws on the 5 looper thread to draw it taut before the point of the needle enters between said looper thread and the body of the looper. If the looper thread is slack at this time, the needle will not enter with certainty between 10 said thread and the body of the looper, but by this thread controlling device which draws the thread taut, I am able to position the looper thread so as to avoid any possible chance of the needle skipping the looper 15 thread loop. As the looper rises, slack thread is given thereto, which permits the looper to move across the stitch finger to the other side of the fabric. As soon as the looper is well over the edge of the fabric, 20 it is retracted so as to shed the needle loop. The thread eye 51 at this time moves again away from the fixed thread guide 50 and draws slightly on the looper thread so as to take up any possible slack therein and hold 25 the same while the needle loop is being drawn by the needle loop controlling devices to set the stitch. This drawing on the looper thread also at this time holds the looper thread taut so that when the looper moves 30 forward into the needle loop, there will be no buckling of the needle thread to crowd the needle loop to one side. This is of particular value in this type of machine, where 35 in the needle loop is thrown upward against the action of gravity thereon, and any slight friction on the needle loop might cause the same to be deflected so that the point of the looper would not enter the same.

From the above description it will be apparent that I have provided a looper thread 40 controlling device which takes up and gives up thread twice for each complete cycle of operation of the looper, and that said taking up and giving up of the thread is timed so as to coöperate properly with the needle thread controlling devices and also properly with the irregular movements of the looper. Inasmuch as the movable thread guide is carried by the looper itself, it will also 45 partake of all the irregular movements of the looper which are necessary to this particular type of machine.

Mounted on the looper is a spreader 52, 55 which projects beneath the looper and engages the needle thread running from the eye of the needle to the fabric, and depresses the same so as to assist the needle in entering with certainty into the looper thread loop without being interfered with by its own thread. This spreader forms no part 60 of the present invention, but is shown, described and claimed in my co-pending application, Serial No. 575,589, filed August 4th, 1910.

It is obvious that minor changes in the

details of construction and the arrangements of parts may be made without departing from the spirit of the invention, as set forth in the appended claims.

Having thus described my invention, what I claim is:

1. A sewing machine including in combination, devices for supporting and feeding a fabric in substantially a vertical plane, a horizontally reciprocating needle, a looper coöperating with said needle and carrying a looper thread about the edge of the fabric, means for operating said looper, and thread controlling devices for taking up the looper thread and drawing the looper thread taut 75 just as the point of the needle is about to pass between the looper thread and the body of the looper.

2. A sewing machine including in combination, devices for supporting and feeding a fabric in substantially a vertical plane, a horizontally reciprocating needle, a looper coöperating with said needle and carrying a looper thread about the edge of the fabric, means for operating said looper, and thread controlling devices for taking up the looper thread and drawing the looper thread taut 80 just as the point of the needle is about to pass between the looper thread and the body of the looper, said devices also operating to take up the looper thread as the needle loop is shed from the looper.

3. A sewing machine including in combination, devices for supporting and feeding a fabric in substantially a vertical plane, a horizontally reciprocating needle, a looper coöperating with said needle and carrying a looper thread about the edge of the fabric, means for operating said looper, thread controlling devices for taking up the looper thread and drawing the looper thread taut 100 just as the point of the needle is about to pass between the looper thread and the body of the looper, said devices also operating to take up the looper thread as the needle loop is shed from the looper, and needle thread controlling devices for taking up the needle thread as the needle loop is shed from the looper for setting the stitch.

4. A sewing machine including in combination, devices for supporting and feeding a fabric in substantially a vertical plane, a horizontally reciprocating needle, a looper coöperating with said needle and carrying a looper thread about the edge of the fabric, 115 means for operating said looper, thread controlling devices for taking up the looper thread and drawing the looper thread taut just as the point of the needle is about to pass between the looper thread and the body 120 of the looper, said devices also operating to take up the looper thread as the needle loop is shed from the looper, and needle thread controlling devices for taking up the needle thread as the needle loop is shed from the 125

130

looper for setting the stitch, said needle thread controlling devices operating also to pull on the thread as the point of the needle leaves the fabric to assist in the final setting 5 of the stitch.

5. A sewing machine including in combination, devices for supporting and feeding a fabric in substantially a vertical plane, a horizontally reciprocating needle, a looper coöperating with said needle and carrying a looper thread about the edge of the fabric, means for operating said looper, thread controlling devices for taking up the looper thread and drawing the looper thread taut

10 just as the point of the needle is about to pass between the looper thread and the body of the looper, said devices also operating to take up the looper thread as the needle loop is shed from the looper, and needle thread

15 controlling devices for taking up the needle thread as the needle loop is shed from the looper for setting the stitch, said needle thread controlling devices operating also to pull on the thread as the point of the needle

20 leaves the fabric to assist in the final setting of the stitch, said looper and needle thread controlling devices being mounted on and carried by the looper rod supporting the looper.

25 6. A sewing machine including in combination devices for supporting a fabric in substantially a vertical plane, a horizontally reciprocating needle, a needle bar carrying said needle, means for reciprocating

30 said needle bar, a looper coöperating with the needle to form an over-edge stitch, a looper supporting rod, means for actuating said looper supporting rod, a thread guide carried by said looper supporting rod,

35 and a fixed guide coöperating with said thread guide, through which guide the looper thread passes, said fixed guide being so disposed relative to the movable guide that the looper thread is taken up and given

40 up twice for each complete reciprocation of the needle.

7. A sewing machine including in combination devices for supporting a fabric in substantially a vertical plane, a horizontally reciprocating needle, a needle bar carrying said needle, means for reciprocating said

45 needle bar, a looper coöperating with the needle to form an over-edge stitch, a looper supporting rod, means for actuating said looper supporting rod, a thread guide carried by said looper supporting rod, a fixed guide coöperating with said

50 thread guide, through which guide the looper thread passes, said fixed guide being so disposed relative to the movable guide that the looper thread is taken up and given up twice for

55 each complete reciprocation of the needle, and means carried by said looper supporting rod for taking up and giving up the needle thread.

8. A sewing machine including in combination devices for supporting a fabric in substantially a vertical plane, a horizontally reciprocating needle, a needle bar carrying said needle, means for reciprocating said 70 needle bar, a looper coöperating with the needle to form an over-edge stitch, a looper supporting rod, means for actuating said looper supporting rod, a thread guide carried by said looper supporting rod, a fixed 75 guide coöperating with said thread guide, through which guide the looper thread passes, said fixed guide being so disposed relative to the movable guide that the looper thread is taken up and given up twice for 80 each complete reciprocation of the needle, a second thread guide carried by said looper supporting rod, and a second fixed guide coöperating with said second guide on the looper supporting rod, through which last 85 named guides the needle thread passes, said second thread guide on the looper supporting rod being so positioned relative to its coöperating fixed guide that the needle thread is taken up and drawn taut when the 90 looper thread loop is shed from the looper.

9. A sewing machine including in combination devices for supporting a fabric in substantially a vertical plane, a horizontally reciprocating needle, a needle bar carrying 95 said needle, means for reciprocating said needle bar, a looper coöperating with the needle to form an over-edge stitch, a looper supporting rod, means for actuating said looper supporting rod, a thread guide carried by said looper supporting rod, a fixed 100 guide coöperating with said thread guide, through which guide the looper thread passes, said fixed guide being so disposed relative to the movable guide that the looper 105 thread is taken up and given up twice for each complete reciprocation of the needle, a second thread guide carried by said looper supporting rod, and a second fixed guide coöperating with said second guide on the looper supporting rod, through which last 110 named guides the needle thread passes, said second thread guide on the looper supporting rod being so positioned relative to its coöperating fixed guide that the needle 115 thread is taken up and drawn taut when the looper thread loop is shed from the looper, and that the needle thread is drawn taut just as the point of the needle is leaving the fabric.

10. The combination of a needle, means for reciprocating the same in a substantially horizontal plane, a looper, a looper supporting rod for the looper, means for reciprocating said rod, means for oscillating said rod, and means for moving said rod up and down, thread guiding means carried by said looper supporting rod, for the looper thread, and a fixed guide for the looper thread position relative to said movable guide so 125 130

that said movable guide moves away from the fixed guide when the looper is withdrawn from the needle loop to assist in setting the stitch.

5 11. The combination of a needle, means for reciprocating the same in a substantially horizontal plane, a looper, a looper supporting rod for the looper, means for reciprocating said rod, means for oscillating said 10 rod, and means for moving said rod up and down, thread guiding means carried by said looper supporting rod for the looper thread, and a fixed guide for the looper thread positioned relative to said movable guide so 15 that said movable guide moves away from the fixed guide when the looper is withdrawn from the needle loop to assist in setting the stitch, and so that said movable guide moves away from the fixed guide 20 when the looper is positioned for the needle to pass between the looper thread and the body thereof.

12. The combination of a needle, means for reciprocating the same in a substantially 25 horizontal plane, a looper, a looper supporting rod for the looper, means for reciprocating said rod, means for oscillating said rod, and means for moving said rod up and down, thread guiding means carried by said looper 30 supporting rod for the looper thread, and a fixed guide for the looper thread positioned relative to said movable guide so that said movable guide moves away from the fixed 35 guide when the looper is withdrawn from the needle loop to assist in setting the stitch, a second thread guide carried by the looper supporting rod for the needle thread, and a second fixed guide coöperating with said second movable guide, said second fixed guide 40 being so positioned relative to its coöperating movable guide that the needle thread is drawn taut when the needle loop is shed from the looper.

13. The combination of a needle, means 45 for reciprocating the same in a substantially horizontal plane, a looper, a looper supporting rod for the looper, means for reciprocating said rod, means for oscillating said rod, and means for moving said rod up and down, 50 thread guiding means carried by said looper supporting rod for the looper thread, and a fixed guide for the looper thread positioned relative to said movable guide so that said movable guide moves away from the fixed 55 guide when the looper is withdrawn from

the needle loop to assist in setting the stitch and so that said movable guide moves away from the fixed guide when the looper is positioned for the needle to pass between the looper thread and the body thereof, a second 60 thread guide carried by the looper supporting rod for the needle thread, and a second fixed guide coöperating with said second movable guide, said second fixed guide being so positioned relative to its coöperating movable guide that the needle thread is drawn taut when the needle loop is shed from the looper.

14. In a machine of the character described, a looper bar, a looper, a needle bar, a needle, thread eyelets located upon opposite sides and above said looper bar for guiding the threads to the looper and needle, and thread guiding means carried by said looper bar and engaging said threads, said thread 75 guiding means coöperating with said eyelets so as to take up and release the threads.

15. In a machine of the character described, a looper bar, a looper, a needle bar, a needle, thread eyelets located upon opposite sides and above said looper bar for guiding the threads to the looper and needle, and thread guiding means carried by said looper bar and engaging said threads, said thread 80 guiding means coöperating with said eyelets so as to take up and release the threads, and means for adjusting the position of the thread eyelets.

16. In a machine of the character described, a looper bar, a looper carried thereby, a needle bar, a needle supported by said needle bar, a rod adjustably supported by the casing and extending in the same direction as the needle bar and having a thread guide at its outer end, a second rod adjustably mounted on the casing and projecting in the direction of the needle bar, and having a thread guide at its outer end, said thread guides operating to guide respectively the looper and the needle threads, thread guides 90 carried by the looper bar and coöperating respectively with the looper and needle threads for taking up and releasing the same.

In testimony whereof, I affix my signature in the presence of two witnesses.

LANSING ONDERDONK.
